AUTOMOBILE DIRECTIONAL SIGNAL LAMP

Robert W. Temple, South Bend, Ind., assignor to Studebaker-Packard Corporation, Detroit, Mich., a corporation of Michigan

Application June 11, 1956, Serial No. 41,851

Term of patent 7 years

(Cl. D48—32)

Fig. 1 is a front elevational view of an automobile directional signal lamp embodying my new design of the invention; and

Fig. 2 is a side elevational view thereof.

The characteristic features of my design reside in the portions shown by means of full lines in the drawing. The broken line showing of a portion of the fender is for illustrative purposes only.

I claim:

The ornamental design for an automobile directional signal lamp, substantially as shown and described.
